UNITED STATES PATENT OFFICE.

EMANUEL W. HARTMAN, OF OAKLAND, CALIFORNIA, ASSIGNOR TO HARTMAN INTERESTS INC., OF LOS ANGELES, CALIFORNIA, A CORPORATION OF NEVADA.

ANNULAR HEARTH OVEN.

Application filed November 20, 1924. Serial No. 751,022.

My invention relates to an apparatus for extracting gas from bituminous material principally in the form of shale or similar rock formation, and relates particularly to 5 that type of apparatus in which the bituminous material is kept continuously disturbed as it is urged forward during its progress through the apparatus.

In apparatus of this character heretofore constructed the heating medium has 10 been brought into direct contact with the bituminous material causing the material to clog and form a coalescent mass thereby materially interfering with the efficient operation of the apparatus.

The principal object of my invention is 15 to provide a gas extracting apparatus in which the heating medium does not come into direct contact with the material being treated.

Another object of my invention is to provide a gas extracting device embodying a plurality of heating decks in which the temperature of the heat supplied to each of 25 the decks may be separately controlled.

I attain the above objects by the novel construction of my gas extracting apparatus, and other objects and advantages of the invention will appear in the subjoined 30 description of the accompanying five sheets of drawings, in which:

Figure 1 is an elevation of the complete apparatus; the heater is shown in vertical section.

Fig. 2 is a vertical section through the retort and driving mechanism therefor. A number of the middle sections are omitted to more clearly illustrate the construction.

Fig. 3 is a perspective view of one of the 40 deck sections with parts broken away to show some details of construction.

Fig. 4 is a vertical section on line 4-4 of Fig. 3.

Fig. 5 is a plan of the agitator. Fig. 6 is a view in detail of a portion of the first deck section, and the agitator is shown positioned and in vertical section.

Fig. 7 is a diagrammatic plan of the retort to chiefly show the relative position of 50 the steam pipes and the staggered position of the deck openings with respect to each other. The rectangle is the inlet for the material and the outlet is in alignment therewith.

Fig. 8 is a plan in reduced scale of the

view shown in Fig. 1 and turned 180 degrees, the trap being removed from the chute in order to show the opening in the cover plate of the retort. The heater is shown in horizontal section and a complete steam pipe 60 unit leads therefrom to the first deck of the retort.

Referring now to the drawings more specifically, 10 indicates a gas extracting retort constructed in accordance with my invention mounted on the base 11, and is connected to a heater 12 by means of a steam pipe system hereinafter more fully described.

Said retort includes a plurality of steam 70 chamber units 13 disposed one above another and rigidly secured together. Each of said steam chamber units comprises an upper circular deck plate 14 centrally bored and secured at its outer edge to an annular 75 flange 15 of a cast ring section 16. A lower plate 17 similar in shape to said deck plate 14 is spaced therefrom and secured at the outer edge to said ring section 16 near the flange 15, and at its inner edge to the upper 80 deck plate by means of a cylindrical plate 18 which extends slightly above the deck plate.

To permit bituminous material to pass from one deck to another, each of said plates 14 and 17 is cut away to form an opening 19 extending from the ring section 16 to the cylindrical plate 18; the said opening is sealed by means of the depending partition walls 20, forming thereby a steam tight 90 chamber, Figs. 3 and 4.

A vertical shaft 21 extends centrally through the retort and is mounted at its lower end in bearings 22 and at its upper end in bearings 23. Said shaft is geared 95 at its lower end to any suitable power means whereby it may be rotated.

Mounted on the said shaft one above another are a plurality of agitators 24 of wheel like construction. Each of said agitators 100 comprises an outer ring member 25 and an inner ring member 26 rigidly secured to a central boss 27 by means of arms 28. A plurality of vertically disposed plates 29 are connected to and between said inner and outer ring members so as to divide said agitator into sections. The agitators are so constructed and positioned within the retort as to provide one agitator for each deck, the lower edge of each plate 29 being 105 110

slightly spaced from the surface of the deck 14 so as to prevent binding and scraping of the parts; and the outer ring member 25 is of less depth than the section plate 29 and 5 is spaced from the ring section 16 so as to facilitate the escape of gases from the material on the decks and allow for expansion of the parts.

The retort is provided with a cover plate 10 30 having an opening 31 therein, and above which opening is mounted a chute 32 through which the bituminous material passes into the retort. A trap 33 of wheel like construction comprising arm members 15 34 secured to a central boss 35, is rotatably mounted on a shaft 36 in said chute and prevents the escape of gas from the retort through the chute.

A similarly shaped chute 37 and trap is 20 secured to and below the bottom plate 38' of the retort, whereby the refuse and spent material is removed from the retort.

Any suitable mechanical means may be 25 used for rotating the traps 33 and 37, but it has been found preferable if both traps are made of equal size to gear the lower trap 37 so as to revolve faster than the upper-trap 33, so as to allow the spent material to pass out faster than the untreated 30 material enters the retort, otherwise clogging might result.

The cover 30 is centrally provided with a funnel outlet 38 disposed in line with and above the central openings formed in the 35 steam chamber units 13 and through which funnel outlet collects and passes the gases from the bituminous material to a condenser (not shown).

Referring now to the means for heating 40 the bituminous material and particularly to Fig. 3 which shows the path of travel of the steam through a steam chamber unit, and to Fig. 8 which shows the path of travel of the steam through the complete apparatus, 45 a manifold 39 is connected between the retort 10 and the heater 12, and is provided with a plurality of steam pipes 40 leading through the heater and to the steam chambers, one steam pipe to each chamber. A 50 plurality of return steam pipes 41 connect the steam chambers with a similar manifold 39'. The direction of the steam through the steam chambers 13 is shown in Fig. 3 by the arrows; the steam enters through pipe 55 40 at one side adjacent opening 19 and passes around the chamber and out pipe 41 adjacent the other side of the opening and returned to the manifold 39' and through the heater 12 where it is reheated and continues again through the apparatus.

As is shown in Figs. 1 and 8, my improved gas-extracting apparatus has the heating means 12 located at a distance from the retort 10. By this arrangement I avoid 60 the liability to overheat the bituminous ma-

terial during its agitation and travel over and through the decks, a liability arising in other constructions of retorts, in which the heating means is located virtually directly below the means for agitating the bitumi- 70 nous material.

A booster 42 of any suitable construction embodying a fan 43 may be inserted in the steam line between the manifolds to assist the circulation of the steam which is prefer- 75 ably kept at low pressure though high tem- perature.

It will be seen from Fig. 7 that the steam chamber units are placed one above another in such a manner that the openings 19 are 80 in staggered relation to each other, so that when the bituminous material is passed through the chute 33 on to the first deck 14 it is carried by means of the agitator 24 to the next lower opening, where it drops to 85 the deck below and makes a complete circuit of each following deck before dropping through the various deck openings to the discharge chute 37. In this manner the bi- 90 tuminous material is continually disturbed and thoroughly exposed to the heat of the retort and simultaneously reduced.

As many of the heavier gases given off by the bituminous material have a tendency to 95 collect in the lower part of the retort, I prefer to supply the lower decks with a small steam pipe 44 for periodically passing high pressure saturated steam over the decks for driving off these gases through the retort and out. 100

In Fig. 1, I have shown a number of tem- 105 perature registry devices 45, which are connected one to each deck, and also a water supply pipe 46 leading to the manifold 39 for supplying water to the heating system. 110

To shut off or regulate the temperature of the steam supplied to any of the steam chambers 13 in case of leakage or other rea- 115 sons, I provide each steam pipe unit with a valve 47 at the intake and a valve 48 at the outlet of each of the steam chambers 13. In my preferred construction I provide the retort 10, the bottom plate 38' and the steam pipes with a covering of asbestos 49 or other heat retaining medium. 115

Other parts shown in the drawings but not specifically referred to, are ordinary structural parts and need no description.

Obviously many changes may be made in my apparatus without departing from the spirit of my invention, and I do not wish to be limited to the exact construction shown but claim as my invention all forms readable on the allowed claim to this applica- 120 tion. 125

What I claim as my invention and desire to secure by Letters Patent of the United States is:—

In an apparatus of the character de- 130 scribed, the combination of a gas-extract-

ing retort having therein a plurality of the deck; and steam-generating means 15 spaced at a distance from the retort and directly connected with each chamber in order to generate and supply steam to and through each chamber, the steam entering each chamber at the side of one of said 20 partition walls and passing out at the side of the other partition wall and the steam inlet to each of the chambers having means for separately controlling the steam.

10 In testimony whereof, I affix my signature.

EMANUEL W. HARTMAN.
